UNITED STATES PATENT OFFICE.

CALVIN B. PATCH, OF GLENELLYN, ILLINOIS, ASSIGNOR TO WILLIAM H. MINER, OF CHAZY, NEW YORK.

RAILWAY DRAFT-RIGGING.

1,258,939.

Specification of Letters Patent. Patented Mar. 12, 1918.

Application filed January 31, 1916. Serial No. 75,293.

To all whom it may concern:

Be it known that I, CALVIN B. PATCH, a citizen of the United States, residing at Glenellyn, in the county of Dupage and State of Illinois, have invented a certain new and useful Improvement in Railway Draft-Riggings, of which the following is a full, clear, concise, and exact description, reference being had to the accompanying drawings, forming a part of this specification.

This invention relates to improvements in railway draft riggings.

One object of the invention is to provide a draft rigging wherein a single casting is employed to which are transmitted either directly or indirectly all the buffing and pulling shocks.

Another, and more specific object of the invention, is to provide a draft rigging wherein is employed a two-part yoke in combination with a friction gear.

The invention, furthermore, consists in the improvements in the parts and devices and in the novel combinations of the parts and devices as herein shown, described or claimed.

In the drawing forming a part of this specification, Figure 1 is a longitudinal, vertical, sectional view of a draft rigging showing my improvement in connection therewith. Fig. 2 is a horizontal, sectional view of the structure illustrated in Fig. 1 and taken substantially on line 2—2 thereof. And Figs. 3 and 4 are vertical, transverse, sectional views taken substantially on the lines 3—3 and 4—4, respectively, of Fig. 1.

In said drawing, 10—10 denote channel shaped center or draft sills to which is secured a box-like, rear stop casting A, more particularly hereinafter described. Normally abutting said casting A is a friction gear B of a well known type, said gear B being operatively connected to the draw bar 11 by means of a two part yoke C—C, the latter being provided with elongated slots 12 to receive a coupler key 13, the ends of the latter also sliding in elongated slots 14 in the center sills. Another yoke 15 is employed to act as a front stop for the gear in pulling movements, as hereinafter described.

Referring now more particularly to the casting A, the same is provided with an upper wall 16, lower wall 17, side walls 18—18 riveted to the sills, front vertical face 19, and upper and lower longitudinally ex-

tending slots 20—20 in which are received the rear ends of the arms of the yoke 15. Suitable aligned slots are provided in the upper and lower sets of walls of the casting A to receive the key 21, the latter also passing through suitable elongated slots 22 in the arms of the yoke 15. Said key 21 may be held in position by any suitable means such as the wedge shaped cotter 23 which passes through suitable transverse perforations in a depending boss 26 on the underside of the casting A. By referring to Fig. 2, it will be seen that the casting A is recessed at the front corners thereof, as indicated at 27, to thereby accommodate the rear portions of the yoke members C—C.

The friction gear B is of that type wherein is employed a casting having a friction shell or cylinder 28 and integral, twin spring casing 29, the latter having mounted therewithin horizontal, twin arranged springs 30 and the shell 28 having mounted therewithin a plurality of friction shoes 31 and wedge 32, a plurality of rolls 33 being interposed between said wedge and the shoes. The wedge 32 engages the filler block 34 employed on the inner side of the yoke 15 at its forward end.

Each of the members C—C of the two part yoke, which are preferably of like construction, is provided with a rectangular recess 35 near its rear end and in which is adapted to be received one side of the substantially rectangular spring casing 29. Each member C has its forward portion tapered as indicated at 36 and provided with a slot 12, as hereinbefore described. The yoke members fit over the spring casing 29 and readily clear the cylinder or shell 28, as clearly appears from Figs. 2 and 3.

The operation is as follows. In buff, the drawbar presses against the yoke 15 moving the latter rearwardly and thus actuating the friction mechanism, since the combined shell and casing 28—29 is prevented from rearward movement by the casting A. Upon draft, the yoke 15 is prevented from forward movement by the key 21 so that as the draw bar moves forwardly with the two part yoke C—C, the friction shell and casing 28—29 slides forwardly relatively to the wedge and shoes of the friction mechanism, thereby absorbing the shock, as will be understood.

With the construction herein before de-

scribed, only one casting is necessary, the same being so arranged that it securely braces the sills. All the parts are readily removable and by employing a two part 5 yoke I am enabled to use a key connection with the coupler and at the same time the yoke members C—C are independently longitudinally movable to thereby accommodate themselves to the movements of the coupler when the latter is swung radially as 10 occurs when the cars are traveling over curved tracks.

I claim:

1. In a draft rigging, the combination 15 with draft sills, of a rear stop member secured thereto, a shock absorbing mechanism, a draw bar, means connected with said stop member to prevent forward movement of the front member of said mechanism under 20 draft, and means for connecting said mechanism with the draw bar under draft, comprising a two part yoke, one part at each side of said mechanism, each part including a loop arranged vertically.

2. In a draft rigging, the combination 25 with draft sills, of a rear stop member secured thereto, a friction gear having a friction shell, friction shoes and a wedge co-operable therewith and a spring cage, a draw 30 bar, means attached to said stop member arranged to prevent forward movement of the front member of said friction mechanism under draft, and a two part yoke connecting said friction mechanism with said draw 35 bar, and operating said mechanism under draft, each part including a loop arranged vertically.

3. In a draft rigging, the combination 40 with draft sills, of a stop casting secured thereto, a shock absorbing mechanism abutting said casting, a vertically arranged yoke encircling said mechanism and having the ends of its arms keyed to said casting, a draw bar, and a two part vertical yoke connecting 45 said mechanism with said draw bar, the members of said two-part yoke being located outside of the first named yoke.

4. In a draft rigging, the combination 50 with draft sills and a draw bar member, of a rear stop member mounted between and secured to said sills, a cushioning device mounted between said sills, and three vertically arranged loop-shaped elements within which said cushioning device is located,

two of said loop-shaped elements being extended in one direction and the third in the opposite direction, two of said loop-shaped elements being adapted to be keyed to one of said members and the third element to the other of said members. 55

5. A stop casting for draft riggings, comprising a substantially hollow boxlike member adapted to have the side walls thereof secured to the sills, said member being provided with upper and lower longitudinally 60 arranged slots adapted to receive the arms of a yoke, said casting having a bearing face on the front side thereof.

6. A stop casting for draft riggings, comprising a substantially hollow boxlike member adapted to have the side walls thereof secured to the sills, said member being provided with upper and lower longitudinally 65 arranged slots adapted to receive the arms of a yoke, said casting having a bearing face 70 on the front side thereof, and recessed at the front corners, said casting being also provided with vertically arranged slots to receive a connecting key.

7. In a draft rigging for railway cars, 75 the combination with draft sills, of a rear stop casting mounted between and secured to both of said sills, a friction gear including a combined cast friction shell and substantially rectangular spring casing, the 80 latter normally abutting said stop casting, a vertically arranged loop encircling said friction mechanism and detachably keyed at its rear end to said stop casting, and means for operatively connecting said friction 85 mechanism with a draw bar under draft, said means including a two part yoke each 90 part being recessed to thereby loop over said spring casing.

8. In a draft rigging for railway cars, the 95 combination with draft sills and a rear stop casting secured thereto, of a cushioning device mounted between said sills, a draw bar, a pair of vertically arranged loop-shaped elements keyed to said draw bar and within 100 which said cushioning device is located, and a third loop-shaped member mounted between said other two members and keyed at its rear end to said casting.

In witness that I claim the foregoing I 105 have hereunto subscribed my name this 30th day of Jan. 1916.

CALVIN B. PATCH.
